SHELTER

Alvin E. Miller, Asheville, N.C., assignor to Rondesics,
Inc., Asheville, N.C., a corporation of North Carolina

Filed Mar. 8, 1962, Ser. No. 69,148

Term of patent 14 years

(Cl. D13—1)

FIG. 1 is a top plan view of the shelter embodying my new design.

FIG. 2 is a side elevation of the shelter.

FIG. 3 is a sectional plan view taken through line 3—3 of FIG. 2.

I claim:

The ornamental design for a shelter, as shown.
